CLAIM

I claim the ornamental design for a point of sale display, as shown and described.

DESCRIPTION

FIG. 1 is a front view of a point of sale display according to the present invention.

FIG. 2 is a rear view of the point of sale display of FIG. 1.

FIG. 3 is a right-side view of the point of sale display of FIG. 1.

FIG. 4 is a left-side view of the point of sale display of FIG. 1.

FIG. 5 is a top view of the point of sale display of FIG. 1; and, FIG. 6 is a top view of the point of sale display of FIG. 1.

The broken lines shown in the drawings form no part of the claimed design.
